UNITED STATES PATENT OFFICE.

CHARLES RUBEN, OF PITTSBURGH, PENNSYLVANIA.

NECKTIE-FASTENER.

1,371,707.

Specification of Letters Patent. Patented Mar. 15, 1921.

Application filed January 30, 1919. Serial No. 274,022.

To all whom it may concern:

Be it known that I, CHARLES RUBEN, a citizen of the United States of America, residing at Pittsburgh, in the county of Allegheny and State of Pennsylvania, have invented certain new and useful Improvements in Necktie-Fasteners, of which the following is a specification.

This invention relates to neck-tie fasteners, adapted for use in connection with four-in-hand and bow ties, more particularly four-in-hand ties, and has for its object to provide a device of such class, in a manner as hereinafter set forth, with means for quickly securing and retaining the tie to and on a collar without necessitating the tying thereof or the inserting of a portion of the tie between the folds of the collar.

A further object of the invention is to provide, in a manner as hereinafter set forth, a neck-tie fastener which is connected to the tie, and which is so set up that it can be quickly and conveniently attached to one of the flaps or ends of the collar whereby the tie will be arranged and secured in position for wear.

A further object of the invention is to provide, in a manner as hereinafter set forth, a neck-tie fastener which when employed in connection with a four-in-hand tie will cheapen the cost of manufacture thereof.

A further object of the invention is to provide, in a manner as hereinafter set forth, a neck-tie fastener which can be adjustably clamped to the collar so that the tie can be set in the position desired.

Further objects of the invention are to provide, in a manner as hereinafter set forth a neck-tie fastener which is simple in its construction, strong, durable, efficient and convenient in its use, readily attached or secured with the tie, and comparatively inexpensive.

With the foregoing and other objects in view the invention consists of the novel construction, combination and arrangement of parts as hereinafter more specifically described and illustrated in the accompanying drawings wherein is shown an embodiment of the invention, but it is to be understood that changes, variations and modifications can be resorted to which come within the scope of the claims hereunto appended.

In the drawings wherein like reference characters denote corresponding parts throughout the several views:

Figure 1 is an elevation of a four-in-hand tie and collar showing the adaptation therewith of a fastener in accordance with this invention, the fastener connecting the tie to the collar.

Fig. 2, is a rear elevation, broken away, of one end of a collar and also of a tie and further showing the tie connected with the collar end by a fastener in accordance with this invention.

Fig. 3, is a rear elevation of a tie, broken away, showing the adaptation therewith of a fastener in accordance with this invention.

Fig. 4, is a perspective view of the head piece of the fastener.

Fig. 5 is a perspective view of the clamping element of the fastener.

The drawings illustrate by way of example the adaptation of a neck-tie fastener in connection with a four-in-hand neck-tie, but it is to be understood that the fastener can be employed for use in connecting a bow tie to a collar.

Referring to the drawings in detail the knot or head of a four-in-hand tie is indicated at 1, and the ends of the tie at 2. The collar formed by an inner and outer fold 3, 4, respectively, has its inner fold 3 extended to provide an end or flap 5, and also an end or flap, not shown, and which is overlapped by the flap 5. The flaps have button-holes. It will be stated that the collar is that of known constructions or shape.

The fastener comprises a head-piece and a clamping element carried thereby, and said head-piece consists of a pair of curved bars 6, 7, each corresponding in contour and opposing each other. Each of the bars 6, 7 is formed with enlarged end portions 8 connected together by a narrow intermediate portion. The inner edges of the enlarged end portions 8 are outwardly and upwardly inclined and the corners of said end portions 8 are beveled. The bars 6, 7 are connected together by overlapping straps 9, 10. The straps 9 extend around the end portions 8, and the strap 10 around the narrow intermediate portions of the bars 6, 7.

The head-piece is extended through the upper portion of the knot or head 1 of the

tie and the material forming the latter is extended and is employed to cover the extending ends of the head piece, or in other words the head piece is completely covered by the material from which the tie is made. The extended ends of the head-piece when the tie is worn are positioned between the outer and inner folds of the collar and between the flap 5 and the 10 outer fold 4, as clearly illustrated in Fig. 1.

The clamping element consists of an inner and an outer clamping member 11, 12 respectively, as shown formed from a metallic strip of resilient material bent upon 15 itself, but it is obvious that the clamping members can be formed of two pieces of suitable material and secured together at one end.

The clamping member 11 is in the form 20 of a bow-shaped spring and is of greater length than the clamping member 12. The member 12 is arranged at the front of the member 11 and does not extend entirely across the front face of the said member 11.

The member 12, at a point between its center and that end which merges with the member 11, that is the outer end of the member 12, is provided with an outwardly 30 curved portion 13, which is reversely curved with respect to the curvature of the remaining portion of the member 12. The free end of the member 12 is bent to extend outwardly to facilitate the connecting of 35 the fastener with the flap 5.

The member 11 is secured between the bars 6, 7 and conforms in curvature to the contour of said bars. The member 11 projects from one end of the head-piece. The 40 bend formed between the members 11 and 12, provided by bending the strip from which the clamping element is formed, extends around one end of the bar 6 outwardly, so that the clamping member 12 45 will be positioned exteriorly, with respect to the bar 6 and the material which incloses the head-piece. The length of the clamping member 12 is such that it will extend at the rear of the head or knot 1 of the tie.

50 The fastener when set up forms a permanent part of the tie. When the tie is to be connected to the collar, the flap 5 is slipped between the clamping member 12 and the head or knot of the tie. This will securely 55 connect the tie in position and does not in-

terfere when buttoning the flaps of the collar to the collar button.

The shape of the clamping member 12 is such that it tends to bind against the flap 5, which firmly holds against the head or 60 knot of the tie, the latter being reinforced by the head-piece, and under such conditions the tie is retained in the position to which it has been set.

What I claim is—

1. A neck-tie fastener comprising a head-piece adapted to be secured to the tie and consisting of a pair of opposed correspondingly curved longitudinally extending bars connected together at their opposed ends, 70 and a clamping element, said element comprising an inner and an outer clamping member, said inner member carried by the head-piece and said outer member arranged exteriorly of the head-piece.

2. A neck-tie fastener comprising a curved head-piece adapted to be secured to the tie and consisting of a pair of opposed correspondingly curved longitudinally extending bars connected together at their 80 opposed ends, and a curved clamping element, said element comprising an inner and an outer opposed clamping member connected with each other, said inner member secured with the head-piece and said outer 85 member arranged exteriorly of the head-piece.

3. A necktie fastener comprising a head-piece adapted to be secured to the tie and consisting of a pair of opposed correspondingly curved longitudinally extending bars connected together at their opposed ends, and a clamping element, said element consisting of an inner and an outer curved 90 opposed clamping member, said inner member secured to the head-piece and connected with the outer member, said outer member arranged exteriorly of the head-piece.

4. A neck-tie fastener comprising a head-piece adapted to be secured to the tie, and 100 a clamping element, said element consisting of an inner and an outer curved clamping member, said inner member carried by the head piece and said outer member arranged exteriorly of the head-piece and having a 105 portion of its length reversely curved with respect to the remaining portion thereof.

In testimony whereof I affix my signature.

CHARLES RUBEN.
